W. I. TUTTLE

CONSTRUCTION FOR BEAMS AND THE LIKE

Filed April 26, 1921

UNITED STATES PATENT OFFICE.

WALTER I. TUTTLE, OF PROVIDENCE, RHODE ISLAND, ASSIGNOR TO FRANK MOSSBERG COMPANY, OF ATTLEBORO, MASSACHUSETTS, A CORPORATION OF RHODE ISLAND.

CONSTRUCTION FOR BEAMS AND THE LIKE.

Application filed April 26, 1921. Serial No. 464,759.

To all whom it may concern:

Be it known that I, WALTER I. TUTTLE, a citizen of the United States, and a resident of Providence, county of Providence, and 5 State of Rhode Island, have invented an Improvement in Constructions for Beams and the like, of which the following is a specification.

This invention relates to the construction 10 of beams and the like, and more particularly to the head construction of such devices. One of the objects thereof is to provide a practical construction of the above nature which shall be light and yet rigid and durable. Another object is to provide a 15 construction of the above nature in which wooden members are efficiently employed and reliably held in assembled relation. Other objects will be in part obvious and in part 20 pointed out hereinafter.

The invention accordingly consists in the features of construction, combinations of elements and arrangement of parts which will be exemplified in the structure herein- 25 after described and the scope of the application of which will be indicated in the following claims.

In the accompanying drawing in which is shown one of various possible embodiments of this invention,

Figure 1 is a sectional elevation taken on the line 1—1 of Figure 2; and

Figure 2 is an end view of the construction shown in Figure 1.

Similar reference characters refer to 35 similar parts throughout both views of the drawing.

Referring now to Figure 1 of the drawing, there is shown a head comprising three built 40 up wooden elements 10, 11 and 12. Each of these elements comprises a plurality of wooden members connected edge to edge as along the lines 13, to form a disk of suitable diameter. The two outer elements 10 and 12 45 lie with the grain of the wood in the same direction, whereas in the intermediate element 11 the grain of the wood lies in the direction at right angles to that of the outer element. It is to be understood that in the 50 case of each of these elements the grain of the wood is substantially parallel to the plane of the head as a whole and is lengthwise of the individual members of which the head elements are composed. At the

point of junction along the edges of the 55 various members they are secured to the contiguous members preferably by glue, although other securing means may be employed if desired.

The outer edge of the wooden head element 10 is preferably curved or beveled as indicated at 14 and the edge portion of the element 11 is curved or beveled in a reverse direction, as indicated at 15, to register at its inner edge with the unbeveled edge of 60 the element 12 as shown at 16.

At the inner side of the head is a metallic 65 head member 17 formed of sheet metal and extending outwardly,—by which is meant a direction away from the axis of the beam, 70 to a point 18 slightly beyond the edge 16. From this point the member 17 is flanged and the flange bent downwardly and thence upwardly, terminating in the portion 19 which rests against the edge 15 of the part 75 11. Although there is no clamping action of this flange, it snugly fits the edge 15 and rests tightly against the inner surface of the wooden head members to which it is secured, as hereinafter described.

On the opposite side of the head is a disk 80 or collar 20 provided with a central hole which registers with the bore 21 through the wooden head members and the sheath 17.

This member 20 is rigidly clamped to the 85 member 17 by a series of rivets 22 which are countersunk, and upon being headed into position, hold the various parts dependably against separation in an axial direction. Furthermore the member 17 is provided with a series of openings 23 circumferentially spaced about its outer portion as 90 shown in Figure 2 of the drawing. The edge of the metal member 17 about these openings is beveled or countersunk on the 95 exposed side of the member as shown in the drawing. Fitted within these countersunk holes 23 are flat headed screw bolts 25, the opposite ends of which rest within recesses 26 extending partially through the head element 10. The nuts 27 upon these bolts are provided with washers 28 and the outer portions of the wooden elements are thus 100 securely clamped against the rigid metal sheath 17. This not only prevents separation of the wooden members at their outer portions but holds them against the rigid metallic head part 17 which acts thus not 105

only as a lining for the head but as a support against which the wooden members are securely clamped.

- The barrel of the beam is shown at 29 and is preferably of the hollow wooden type built up of sectors and provided at its end with an abutment 30. Between this abutment and the head is a metal or wooden spacing collar or block 31. The shaft 32 10 passes through the barrel and collar as well as the head, and at its outer end is threaded to receive the nut 33 by which the head is clamped tightly against the end of the barrel.
- 15 As various possible embodiments might be made of the above invention and as various changes might be made in the embodiment above set forth, it is to be understood that all matter herein set forth or shown in 20 the accompanying drawing is to be interpreted as illustrative and not in a limiting sense.

I claim as my invention:—

1. In construction for beams and the like, 25 in combination, a metallic head member bent laterally at its outer edge to form a belt race, a head member built up of wooden sections, the grain of the wood in one section being crossed with respect to the grain 30 of the wood in another section and said head member being inserted within the bent-over portions of said first member and having its periphery substantially encased thereby, and means adapted to secure said wooden member to said metallic member.
2. In construction for beams and the like, 40 in combination, a metal head member of a diameter substantially equal to that of the head, a second metal member of smaller diameter and substantially parallel to said first member, a built-up wooden head member clamped between said metal members, and a plurality of securing devices holding 45 said wooden head member against said first metal head member at points outwardly spaced from said second metal head member.
3. In construction for beams and the like, 50 in combination, a metal head member of a diameter substantially equal to that of the head, a second metal member of smaller diameter and substantially parallel to said first member, a built-up wooden head member clamped between said metal members, and a plurality of securing devices holding 55 said wooden head member against said first metal head member at points outwardly spaced from said second metal head member, said wooden head member comprising a plurality of sections one of which has its 60 grain crossed with respect to one or more of the others thereof.

4. In construction for beams and the like, in combination, a metal head member having a diameter substantially that of the head, a metal head member of relatively small diameter lying parallel thereto, a built-up wooden head member interposed between said metal members and comprising a plurality of sections each of which has a plurality of parts secured edge to edge, means securing said metal members one to another and clamping said wooden member therebetween, and means securing said wooden member to said first metal member at points outwardly spaced from said second metal member.

5. In construction for beams and the like, in combination, a barrel, a metal head member resting against the end of said barrel, a built-up wooden head member substantially equal in diameter to said metal member and resting against the same on the side remote from said barrel, a metal member resting against the side of said wooden member remote from said barrel, means bearing against said second metal member and holding said head against said barrel, and means securing said wooden head member to said first metal member at points outwardly spaced from said second metal member.

6. In construction for beams and the like, in combination, a barrel, a metal head member resting against the end of said barrel, a built-up wooden head member substantially equal in diameter to said metal member and resting against the same on the side remote from said barrel, a metal member resting against the side of said wooden member remote from said barrel, means bearing against said second metal member and holding said head against said barrel, and means securing said wooden head member to said first metal member at points outwardly spaced from said second metal member, said first metal member having its outer portions substantially encasing the periphery of said wooden member and having a belt race formed therein.

7. In construction for beams and the like, in combination, a pair of metal head members, and a wooden head member comprising a plurality of sections clamped between said metal members, said first metal member being provided with a lateral extension at its outer portion embracing said wooden member substantially encasing its periphery and forming a belt race about the same.

In testimony whereof, I have signed my name to this specification this 22nd day of March, 1921.

WALTER I. TUTTLE.
